UNITED STATES PATENT OFFICE.

JOHANN HEINRICH KLERX, OF SUNBURY, PENNSYLVANIA, ASSIGNOR
TO SUSQUEHANNA SILK MILLS, OF SUNBURY, PENNSYLVANIA, A
CORPORATION OF PENNSYLVANIA.

MEANS FOR CONTROLLING LOOMS BY THE QUANTITY OF WEFT IN THE SHUTTLES.

SPECIFICATION forming part of Letters Patent No. 723,879, dated March 31, 1903.

Application filed February 4, 1902. Serial No. 92,564. (No model.)

To all whom it may concern:

Be it known that I, JOHANN HEINRICH KLERX, a citizen of the United States, and a resident of Sunbury, county of Northumberland, and State of Pennsylvania, have invented a new and useful Improvement in Means for Controlling Looms by the Quantity of Weft in the Shuttles, of which the following is a specification.

10 My invention relates to looms, and more particularly to means for controlling a loom by the quantity of weft in a shuttle thereof.

The objects of the invention are more particularly directed to improvements in the 15 construction of the shuttle and the parts thereof adapted to coöperate with filling-exhaustion-detector devices that may be of any well-known type.

I will describe a mechanism embodying 20 my improvement and then point out the novel features in the claims.

In the accompanying drawings, Figure 1 is a plan view of portions of a loom, including 25 a shuttle-box and shuttle, in which my invention is embodied. Fig. 2 is a section taken on the plan 2 of Fig. 1. Fig. 3 is a view from the interior of the shuttle and looking toward the movable plate Y therein.

Similar letters of reference designate 30 responding parts in all the figures.

A designates one shuttle-box of a loom, mounted upon and carried by the lay of the loom, as usual. This shuttle-box is provided on that side which is toward the breast-beam 35 of the loom with an opening or aperture a.

B designates a shuttle, which may be of ordinary form, except that it is provided at one side with an opening or aperture b, having an upwardly-projecting rib b', the purpose of which will be described hereinafter.

b² represents the spindle of the shuttle, and it may be of any usual form. It is shown as hinged at one end to the body of the shuttle by means of a pin b³.

45 D designates a device for coöoperating with the body of weft in the shuttle B. It may be termed for convenience an "engaging" device or "feeler." It consists of a main portion D', fitted to slide in bearings at d⁴

and d⁴ upon a stationary part of the loom, 50 and a hinge portion d, provided with a flat spring d⁵, that is connected to the main portion D' of the feeler and acts upon the hinge portion d by pressing it downwardly to turn it about the hinge d². The feeler D is adapted 55 to enter and coöperate with the body of weft in the shuttle, as above stated, and its purpose is upon substantial exhaustion of the weft or exhaustion to a predetermined point to effect or bring about the operation of a 60 loom-stop or filling-renewing mechanism. The portion d of the feeler D is adapted to engage with the above-mentioned rib b', that is carried by the shuttle B, whenever the weft being exhausted to a predetermined 65 point the lay beats up and the part d thereby enters the shuttle sufficiently to permit engagement with the said rib b'. The sliding or reciprocation of the bars D' is limited by a suitable stop or stops, which in the present example are shown as the pins d⁶ d⁷, 70 adapted to abut against the bearings d⁸ d⁹. To prevent a recoil of the bar D' after contact of its stop-pin D⁷ with the bar D⁴, it is advantageous to provide a spring-detent d¹⁰ 75 for engaging a notch d¹¹, formed in the said bar D', the said detent being supported upon and actuated by a flat spring d¹². At the end of the bar D' farthest from the lay is provided a part d¹³ for engaging a cam device, which will now be described.

E represents a pivoted lever with a pivot at e and comprising at one portion a cam-surface E', that is substantially radial, and a second cam-surface E², forming a continuation 85 of the cam-surface E', but at an angle thereto. The part d¹³, carried by the slide D', is normally in engagement with the cam-surface E', as shown in Fig. 1, and to preserve such engagement a spring e' may be provided, acting upon a rod e², fitted to slide within a bearing formed at e⁵ in the stationary part of the loom, the said rod e² pressing against the lever E' to move it toward the left in said figure. Connected to the lever E is shown a 95 rod G, which may conveniently be the actuating means for a loom-stop or weft-renewing mechanism. (Not shown.) The loom-stop

or weft-renewing mechanism may be of any suitable or well-known form. A rod f is fitted to slide in bearings formed at e^3 e^3 on the lever E. It is provided with a stop f' for engagement with one of the bearings e^3 and a spring F, preferably surrounding the rod f and also for convenience acting upon the stop f' in such manner as to move the rod f toward the lay of the loom. This rod f extends through the bearing e^3 and is normally in engagement with the part d^{12} of the slide D', the purpose of the rod f being to actuate the rod D' to maintain it in a normal position.

The hereinbefore-described mechanisms are shown as being similar in construction and arrangement to the construction illustrated in Patent No. 689,550, issued to me on December 24, 1901, and the operation thereof will be similar to the operation described in said prior patent. I do not in the present application attempt to claim the hereinbefore-described parts, except in combination with certain improvements that will be described hereinafter, nor do I wish to be limited in the present application to the use of a feeler device constructed in exact accordance with the said prior patent, as any well-known or suitable feeler device or devices for coöperating with the body of weft in the shuttle may be employed in connection with the present invention without departing from the spirit thereof.

Y represents a plate, which may be of any suitable material and is fitted within the shuttle B to move inwardly and outwardly therein intermediate of the body of weft in the shuttle and the aperture b in the shuttle side. The said plate is shown as hinged about an axis at y' , fitted to the shuttle side, this being a convenient means to permit the inward and outward movements of the plate. The plate Y is also preferably flat in form, so that it may rest snugly against the inner side of the shuttle, and is for convenience provided with a spring y, having a tendency to force the plate toward the shuttle side. The plate Y is intended to extend over the opening or aperture b in the shuttle side to any suitable extent, but preferably entirely across the said aperture. The said plate Y may be said to constitute a detector, as it is adapted to engage with the body of weft when moved inwardly, and therefore the quantity of weft remaining in the shuttle will determine the inward limit of movement of the plate or detector Y. It will be understood that the feeler device D is adapted to enter into the shuttle through the aperture b and to coöperate with the body

of weft, not by contacting directly with the weft, but through the agency of the plate Y, which may therefore be termed an "intermediate" plate. It will be noted that the plate Y does not extend longitudinally beyond either end of the body of weft, and this is an advantage, because it avoids danger of the said detector or plate Y striking any part of the shuttle beyond the end of the weft-body and interfering with the proper operation of the feeler device D. It also permits of a more compact and a lighter design of detector-plate. These advantages are also afforded by the employment of an axis arranged longitudinally of the shuttle.

What I claim as my invention is—

1. In a loom the combination with a shuttle-box, having an aperture in its side, a shuttle having an aperture corresponding to the aperture in said shuttle-box, a feeler device constructed and fitted to enter the shuttle to co-operate with the body of weft therein, mechanism operated by said feeler device for bringing about or controlling the operation of a loom-stop, or filling-renewing mechanism, and an intermediate plate fitted within the shuttle to swing inwardly and outwardly about an axis arranged longitudinally of the shuttle, to extend over or across said aperture when in outward position, and to contact the body of weft when in inward position, and a spring arranged to act upon said intermediate plate to retain it normally in outward position.

2. In a loom the combination with a shuttle-box, having an aperture in its side, a shuttle having an aperture corresponding to the aperture in said shuttle-box, a feeler device constructed and fitted to enter the shuttle to co-operate with the body of weft therein, mechanism operated by said feeler device for bringing about or controlling the operation of a loom-stop and filling-renewing mechanism, and an intermediate plate fitted within the shuttle to swing inwardly and outwardly about an axis arranged longitudinally of the shuttle to extend over or across said aperture when in upward position, and to lie wholly between the end portions of the body of weft when in inward position, and a spring arranged to act upon said intermediate plate to retain it normally in outward position.

In testimony whereof I have signed my name to this specification in the presence of two subscribing witnesses.

JOHANN HEINRICH KLERX.
